ABSTRACT: A centrifuge of the type which has a central slurry feed pipe, a rotating bowl, and a concentric conveyor which includes a tubular shaft with a helix on the outside. The shaft has rectangular openings in the area of the slurry feed with rectangular orifice plates of hardened material fastened inside the shaft. The orifice plate is sealed to the shaft so that it forms a lip, retaining a pool of slurry within the shaft. The orifice plate is also smaller than the opening and overlaps the trailing edge of the opening.

CENTRIFUGE SLURRY SUPPLY

BACKGROUND OF THE INVENTION

This invention relates to centrifuges for separating solids from liquids and in particular to an arrangement for feeding the slurry into the rotating bowl of a centrifuge.

In centrifuges of the type contemplated, the bowl rotates at high speed to develop the centrifugal force which separates the liquid and solids. Within this rotating bowl a conveyor is rotated also at high speed, but at a speed varying slightly from that of the bowl. A helix on the outside of the conveyor operates to urge the solids towards the solids discharge end due to the differential rotation between the conveyor and the bowl. A stationary slurry feed pipe is centrally located to introduce the material into the centrifuge. The slurry must, therefore, pass through the conveyor shaft before it gets to the bowl.

Due to requirements of stiffness and strength, the conveyor is generally formed of a large hollow tubular shaft. One method of allowing the slurry to pass therethrough has been to use simple round openings in the shaft. This results in a concentrated stream of slurry passing into the bowl. In operation a layer of the solid material forms on the bowl surface underlying the slurry at any given time. This layer of solids has been found effective in improving the balance of the centrifuge and in promoting the separation of the very fine particles. It is believed that this buildup inherently reduces the clearance and therefore leakage between the rotating conveyor helix and the rotating bowl. The stream of slurry from these round openings has been found to create such an impact in the bowl that it disturbs this underlying layer of solids so that separation in a centrifuge is reduced with excessive solids being carried into the liquid effluent.

Tubular nozzles either extending radially outward from the shaft or generally tangent to the shaft have been added in some designs to reduce this turbulence. These nozzles operate to increase the angular speed of the discharge through shaft to a lower relative velocity when the stream strikes the pool in the bowl. This has been effective to increase stability of the centrifuge and improve its separating performance.

Extensive wear has occurred on these nozzles particularly on the trailing edge where most of the solids in the slurry would tend to concentrate. This has resulted in the trailing edge of the nozzles wearing through, requiring shutdown and replacement. The use of hardened material in the nozzles would slowdown the wear, but it is very expensive to form these hardened materials in the shape of nozzles and to fasten them securely to the shaft when they must withstand the forces due to the high rotating speed.

Since the slurry is dumped in the inside of the rotating shaft of the conveyor, extensive wear occurs as the solid materials slide circumferentially along the interior surface of the shaft. This creates a wear problem at this location which is critical, since thinning of the shaft would decrease its stiffness and strength. This cannot be tolerated in view of the high speed and high forces which occur in a large centrifuge.

SUMMARY

In my invention the opening through the conveyor shaft through which the slurry flows is rectangular in shape, or at least has the trailing edge generally linear and parallel to shaft axis. A similarly shaped orifice plate of hardened material may be fastened inside the shaft and sealed around the edges, thus forming a dam around the openings. The trailing edge of the orifice plate overlaps the opening through the shaft.

The use of the rectangular orifice plate and the straight trailing edge spreads the flow of slurry evenly across the orifice opening. This results in a wider, less concentrated stream of slurry into the bowl which causes only surface disturbance of the material in the bowl avoiding the penetration that occurs when a round opening is used. The straight edge also avoids the concentration of solids in one location so that wear is spread uniformly across the orifice plate. While in a tubular

outlet under transverse acceleration, a rotational flow through the cross section of the pipe is set up increasing wear. This does not occur with a rectangular opening.

The orifice plate is simply mounted on the inside of the shaft with the centrifugal force of rotation helping to keep the orifice plate against the shaft. The trailing edge of the orifice can overlap the orifice opening at the trailing edge of the opening. In this manner most, if not all, of the wear occurs on the orifice plate which is made of a hardened material with minimal wear occurring in the shaft.

The orifice plate can be sealed around the opening so that it forms a dam within the shaft. This results in a pool of slurry building up inside the shaft which rotates at the speed of the shaft. The slurry being added meets this rotating pool rather than the shaft itself thereby avoiding excessive erosion of the shaft material. The rotating pool, however, serves to accelerate the slurry being fed toward the speed of the shaft thereby achieving some angular velocity before the discharge through the orifice into the bowl.

BRIEF DESCRIPTION OF THE DRAWINGS

FIG. 1 is a general arrangement of a centrifuge;

FIG. 2 is a detailed sectional side elevation in the area of the openings through the conveyor shaft;

FIG. 3 is a side sectional view of the orifice plate opening through the shaft; and

FIG. 4 is a plan view of FIG. 3.

DESCRIPTION OF THE PREFERRED EMBODIMENT

Within casing 12 of the centrifuge a slurry of water and coal is supplied through centrally located slurry feed pipe 13. The slurry is discharged through the opening 14 and ultimately reaches the interior of rotating bowl 15. Water is discharged through opening 17 and discharge spout 18. The solids which are separated from the slurry are urged in the opposite direction passing outwardly through opening 19 and pipe 20.

This longitudinal movement of the solids is accomplished by use of rotating conveyor 22. While the bowl 15 is rotating at about 1,000 r.p.m., the conveyor shaft is rotating at only 1,010 r.p.m. This differential rotation of 10 revolutions per minute operates to urge the solid coal particles towards the discharge end by means of the helical flights 23. These helical flights are mounted on a generally impervious tubular frame 24 of the conveyor.

Discharge from the slurry feed pipe 13 passes to the rotating bowl through the rectangular openings 27 in the shaft. Four of these openings are located around the periphery of the shaft at different longitudinal positions. Each of the openings occurs at a location between the locations of the flights. Each opening is 4 $\frac{1}{4}$ inches in the longitudinal direction and 3 inches wide with at least the trailing edge being parallel to the shaft axis. Since the rotating shaft must be stiff in order to maintain the clearance between the flights and the bowl and must also be strong due to the high forces encountered, the material removed from the shaft should be minimized. The length of the openings, therefore, is relatively large with the 4 inch openings amounting to over two-thirds of the distance available between flights. The slurry flows out along the trailing edge of the opening of this rotating shaft. Therefore, a 4 inch wide stream flows from each opening into the bowl. By spreading this stream out into 4 inch wide streams, a relatively thin stream is formed at each location so that impact in the bowl is minimized.

Inside each opening in the shaft an orifice plate 28 is mounted. This plate may be of alumina or any other wear resistant material. The opening in the orifice plate is also 4 inches long but only 2 $\frac{1}{2}$ inches wide with the trailing edge 29 of the plate overlapping the opening in the shaft by $\frac{1}{2}$ inch. Referring to FIG. 3 since the rotating bowl 24 is moving at high speed to the left, the relative direction of discharge through the openings would be upwardly and to the right. The overlap of this orifice plate prevents excessive wear from oc-

curring on the relatively soft material on the shaft so that essentially all wear occurs on the orifice plate itself.

Since it is very difficult to form complicated shapes of a hardened material, a relatively simple form is used. The orifice plate is maintained in place by the use of holdown plates 30 which overlap the orifice plate 30 and are bolted to the shaft with bolts 32. These bolts pass from the outside of the shaft so that no wear occurs on the head of the bolts. Centrifugal force tends to maintain the orifice plate in position while the centrifuge is in operation. A rubber gasket 33 is placed between the orifice plate and the shaft. This soft gasket not only reduces breakage of the relatively brittle orifice plates in the event of a slight mismatch of surfaces but also effectively seals against leakage between the orifice plate and the shaft. The orifice plate operates as a dam so that a rotating pool of slurry is formed inside the conveyor shaft. Flow passing from the slurry pipe 13 into the interior of the shaft impinges on this pool rather than on the shaft itself so as to avoid excessive sliding and wear of the shaft. The rotating pool, however, operates to accelerate the slurry being fed to an angular velocity approaching that of the conveyor shaft so as to reduce the relative velocities when the slurry passes onto the bowl.

While I have illustrated and described a preferred embodiment of my invention it is to be understood that such is merely illustrative and not restrictive and that variations and modifications may be made therein without departing from the spirit and scope of the invention. I therefore do not wish to be limited to the precise details set forth but desire to avail myself of such changes as fall within the purview of my invention.

What I claim is:

1. A centrifuge for separating a slurry into its solid and liquid components comprising: a centrally located slurry feed pipe; a rotating bowl concentric with said feed pipe; a rotating conveyor within said bowl and concentric of said slurry feed pipe which rotates at a speed slightly different than said bowl, said conveyor having a generally impervious tubular shaft and

having on the outer portion of said shaft means to urge solids longitudinally along said bowl; said feed pipe feeding slurry to the interior of said shaft at a feed location; said shaft having openings therethrough in the area of the feed location; and said openings having at least a trailing edge generally linear and parallel to the axis of said shaft.

2. An apparatus as in claim 1 wherein said openings are rectangular.

3. An apparatus as in claim 2 having rectangular orifice members fastened inside said shaft at the location of said openings.

4. An apparatus as in claim 3 wherein said orifice members are fastened to the inside of said bowl in a fluidtight manner whereby the orifice effectively forms a dam resulting in a rotating pool of slurry within said shaft.

5. An apparatus as in claim 3 wherein said orifice members overlap said openings on the trailing edge thereof.

6. An apparatus as in claim 5 wherein said orifice openings have a length longitudinal to the shaft greater than the width of the opening.

7. An apparatus as in claim 6 wherein said openings are longitudinally offset relative to one another.

8. An apparatus as in claim 1 having orifice members fastened inside said shaft at the location of said openings, said orifice having at least a trailing edge generally linear and parallel to the axis of said shaft.

9. An apparatus as in claim 8 wherein said orifice members are fastened to the inside of said bowl in a fluidtight manner whereby the orifice effectively forms a dam resulting in a rotating pool of slurry within said shaft.

10. An apparatus as in claim 8 wherein said orifice members overlap said openings on the trailing edge thereof.

11. An apparatus as in claim 1 wherein said openings are longitudinally offset relative to one another.
